UNITED STATES PATENT OFFICE.

ROBERT C. McCALEB, OF WATERLOO, IOWA.

DESIGN FOR A PUZZLE-BOARD.

SPECIFICATION forming part of Design No. 34,767, dated July 9, 1901.

Application filed March 25, 1901. Serial No. 52,870. Term of patent 3½ years.

To all whom it may concern:

Be it known that I, ROBERT C. McCALEB, a citizen of the United States, residing at Waterloo, in the county of Blackhawk and State of Iowa, have invented and produced a new and original Design for a Puzzle-Board; and I do hereby declare the following to be a full, clear, and exact description of the same.

My invention relates to a new and original design for a puzzle-board; and the essential features of it consist in a board upon which is printed one or more squares, each of which is composed of smaller figures of angular shape and each smaller figure having a rectangular figure in or near its center.

The following description of the appearance of my design will be set out in the following specification and drawing accompanying the same, in which the figure shows a perspective or plan view of my design.

Referring to the drawing, S represents my puzzle-board, upon which are printed the various figures hereinafter to be described.

A, B, C, D, E, F, and G represent the seven squares, and H the various figures forming these squares. It will be noticed that no two of the figures H are alike; but all of them are formed with angular corners approaching

from an acute angle to a right and obtuse angle, and no two of the exact same size. In 30 or near the center of each block is a rectangular figure K. This figure K is formed in each of the figures H. The square A is bounded on two of its sides by the lines a a. The square B is bounded on two of its sides by 35 the lines b b, the square C by the lines c c, the square D by the lines d d, the square E by the lines e e, the square F by the lines f f, and the square G by the lines g g. The other two sides of all the squares are bounded by 40 the lines h h.

It will be seen that the unique features of this design are the peculiarly-shaped figures, each having a rectangular figure near its center, and all of the figures forming a series of 45 squares of increasing size.

Having now described my design and illustrated its appearance, what I claim is—

A design for a puzzle-board as described and shown in the drawing. 50

In testimony whereof I affix my signature in the presence of two witnesses.

ROBERT C. McCALEB.
